UNITED STATES PATENT OFFICE.

HAMILTON T. HOWELL, OF NEW YORK, N. Y., ASSIGNOR TO ALFRED VESTER SONS, INC.,
OF PROVIDENCE, RHODE ISLAND, A CORPORATION OF RHODE ISLAND.

DESIGN FOR A CEILING PLATE FOR LIGHTING FIXTURES.

Application filed October 28, 1922. Serial No. 4,129. Term of patent 14 years.

To all whom it may concern:

Be it known that I, HAMILTON T. HOWELL, a citizen of the United States, and residing at New York, in the county of New York and State of New York, have invented a new, original, and ornamental Design for a Ceiling Plate for Lighting Fixtures, of which the following is a specification, reference being had to the accompanying drawing, forming part thereof.

Fig. 1 is a side elevation of a ceiling plate for lighting fixtures, showing my new design.

Fig. 2 is a bottom plan view of the same.

I claim—

The ornamental design for a ceiling plate for lighting fixtures, as shown.

HAMILTON T. HOWELL.
